UNITED STATES PATENT OFFICE.

CHARLES H. STROUSE, OF INDIANAPOLIS, INDIANA.

INTERIOR FORTRESS.

Application filed July 9, 1926. Serial No. 121,358.

My invention relates to protective fortresses, and more particularly to interior fortresses, as used for protecting business institutions against banditry; and consists substantially in the construction, combination and arrangement of parts hereinafter set forth and pointed out more particularly in the claims.

An object of my invention is to provide a fortress for the interior of banks and other business places in which may be kept firearms of different kinds, and ammunition at the convenient disposal of the bank watchmen or other employees, and in which they may find shelter and opportunity to counter attack.

The primary object of my invention is to provide a fortress for the interior of banks and other public business houses, such fortress having special observation windows, and special port holes for shooting at hold-up men.

It is one of my main objects to provide an interior fortress in such manner that it has a portion extending out from the main building structure, as an exterior fortification being adapted to serve as a means of observation and shooting at bandits, especially as they are fleeing after committing robbery.

It is a further object to provide private entrance into said fortress from all floors of the institution, including the basement, and a convenient route thru which the bank employees may readily escape from the bandits and find their way in said fortress, whereby they may shoot from behind substantially bullet proof steel faced walls, or the like.

It is also an object to have such fortress extended substantially the full length of the building in overhead manner thru which ample protection may be had for any part of the bank rooms, without loss of floor space to the business itself.

The above and other objects are attained by the structure illustrated in the accompanying drawings, in which: on line 1-1 of Fig. 2, Figure 1 is a sectional plan view showing the floor and walls of a bank building, in conjunction with which my invention is shown embodied, and also the arrangement of the tellers' cages, etc. Fig. 2 is a side sectional view taken in the proximity of line 2-2 of Fig. 1; Fig. 3 is a cross sectional view taken in the proximity

of line 3-3 of Fig. 2; Fig. 4 is a front fragmentary elevation of the building proper, showing the exterior termination of the fortress; and Fig. 5 is a fragmentary cross sectional view illustrating a modified form of the invention as will be understood.

Similar characters of reference designate similar parts thruout the several views. Referring to Fig. 1, the numeral 1 designates the main floor of a banking institution. The numeral 2 designates the front wall of the bank building, the numeral 3, the rear wall, the numeral 4 one of the side walls, numeral 5 the other side wall, and numeral 6 the ceiling.

The tellers' cages 7 face toward the customer's space 8, the money counters 9 being accordingly provided at the front of said cages in conventional manner. The rear of said cages are disposed toward the side wall 4.

The space 10, fenced off by the railing 11 may be used as the office quarters for the active bank officers, and the space 12, for clerical help, as desired. It is understood, however, that since practically no two banks are alike in the matter of arrangement of their fixtures and employees, it is not feasible to restrict my invention to the particular arrangement of any one bank.

My new and novel features are carried into effect by providing an overhead fortress 13, on the order of a hall way or runway. Said fortress is conveniently suspended from the ceiling 6, rearwardly of the cages 7; and is arranged the full length of the banking building, from front wall 2 to rear wall 3.

Said fortress is conveniently constructed by extending the fortress floor 14, thereof, from the side wall 4, in shelf manner, by which arrangement, said side wall serves also as one of the walls of said fortress. Said fortress floor is comparatively narrow as considered in Fig. 3, but quite extensive as shown in Fig. 1 and Fig. 2. On the overhanging edge 15 on said fortress floor a wall 16 extends upwardly and joins the ceiling 6, and serves as the inner fortress wall. The fortress wall 16 and said fortress floor extend forwardly thru the front building wall 2, and rearwardly to the rear building wall 3. In forward continuation of said fortress, an exterior fortification 17 is formed in "bay window" manner, said front building wall being otherwise open at its juncture with said fortress, for commun-

cating said fortification with the fortress proper.

A stair-way 18 leads upwardly from the main floor 1, to the fortress floor 14, a door 19, being provided to give entrance to said stair-way from said main floor. A set of stair steps 20 leads from the basement floor 21, to said stair-way by which said fortress may be reached, without exposure to the public view.

Another set of basement steps 22 is provided, rearwardly of the tellers' cages to which entry thru the especially provided door 23, and stair-way 24, to the basement 25 may be readily made. After entry has thus been effected to said basement, the fortress 13 may be reached by means of the stair steps 20, and the stair-way 18.

The inner wall 16 of said fortress is provided with lookouts 26, and port holes 27, 28, 29, 30, and 31 preferably to the right of each thereof, whereby a person may, while at one of said look-outs, reach out thru the respective port hole with a revolver and make a counter attack upon attacking bandits. It is understood however, that rifles 33 are also kept within the fortress preferably near said port holes, and may be used as well as revolvers, thru said port holes. Said port holes are each provided with hinged doors 34 which are shown in opened position at port holes 27 and 30.

The outer surfaces of the floor 14 and wall 16, in respect to the fortress itself, are faced with substantially bullet proof steel plating 35 or the equivalent, meaning the under surface 36 of said floor and the surface 37 of said wall, which would otherwise be exposed to the interior of the banking room.

The look-outs 26 are constructed by providing window like holes 38 thru the main structure of the fortress wall 16, and providing horizontal slits 39 in the steel plating 35 thru which observations may be made from within the fortress. The metallic strips 40 left between said slits are formed in half punch manner as understood by mechanics, and remain integrally supported at their ends by the adjoining plating 35.

Said strips are thus stationarily disposed, but otherwise resemble the old and conventional window shutters, except that I prefer to form said strips part-cylindrical about an inward horizontal axis which gives same a drooping characteristic.

Inverted-funnel shaped peep holes 41 are provided in the fortress floor 14, thru which observations, and shooting may be carried out, it being understood that said peep holes 60 serve also as a means to secretly scrutinize the conduct of the bank tellers and other employees, to ascertain their diligence, competence or honesty.

One of the important characteristics of my invention lies in the aforesaid exterior

fortification 17, formed on the front end of the fortress 13, having combined port holes and look-outs 42, 43, 44, and 45, which are closable by means of their doors 46, the door of look out 43 being shown open and the others closed.

Banking institutions usually employ one or more police or watchmen as guards who spend considerable time in or near the customer's space 8 in plain view of the public. Such watchmen are usually as helpless in case of a hold up as any other employee of the bank as the bandits give immediate attention to overpowering the police or guards present, before making further procedure.

In institutions where my invention is used, the watchman may spend the most part of his time in the fortress which is always kept supplied with fire arms and ammunition of size, variety and quantity that could not be regularly carried about, and could not be displayed, without undesirable effect upon the public. Shelves 48 are provided near some of said port holes as desired upon which may be kept revolvers 49.

One of the most important advantages in the use of my invention, however, lies in the fact that hold-up men not being familiar with the exact movements of employees within an institution and never being able to ascertain whether or not there is some one on duty in the fortress, will be greatly deterred from making hold-ups by this uncertainty, it being necessary to make more sure of their ground before beginning.

It is also intended that bank employees other than the regular bank police guards may spend time within the fortress, especially when it is necessary for the guard to be relieved from duty.

Chairs 50, and other furniture such as tables 51, or desks are provided along in the fortress to add to the comfort of the occupants, and to also provide a means of doing clerical or other work while on duty, it being understood that the look-outs 26 provide ample means to hear the sounds coming from the confusion of a bank or other open robbery. It will therefore not be necessary for the fortress occupant to be on constant watch at the look-outs.

When bank hold-ups have occurred in the past, the employees and particularly the tellers, have seldom had means of escape, or of fighting the bandits, even if the opportunity occurred. Where my invention is used, however, any employee of the bank may, if the opportunity occurs escape to the fortress 13 by way of the basement 25 thru the door 23, or the usual basement stairs (not shown) or thru the door 19 and directly up the stair-way 18 to said fortress where they not only have bodily protection but where they may with safety shoot at the bandits. Another serious problem in connection

with hold-ups lies in the fact that it has nearly always been very impractical to pursue fleeing bandits after a hold-up has been committed, as such an attempt would expose the pursuers to the open fire of the escaping outlaws, with which, the pursuers are seldom if ever prepared to contend. Where my invention is used some of the bank employees may rush to the fortress as soon as the bandits have fled, and shoot at them from the exterior fortification 17.

Doors 52 are provided for the ventilators 53 which communicate the interior of the fortress 13 with the exterior atmosphere. Said ventilators have double bend conduit characteristics to prevent any great amount of light from entering the fortress, under certain conditions as will be understood.

It is understood that an invention of this class must be adapted to the particular building with which it is embodied. For example the tellers' cages are in some banks arranged along the rear wall of the banking room instead of along the side wall as I have illustrated, in which instance the fortress would extend along both the side and the rear wall of the banking building and would accordingly have a general L plan formation.

In a great many other banks, the tellers' cages are on opposite sides of the banking room, the cages on one side facing those on the other, in which instance it would be appropriate to construct the fortress in dual manner, one such fortress being provided along each side wall of the banking room, which arrangement would afford two exterior fortifications such as 17. If however, a fortress of such dual character is not desired the invention is conveniently carried out by supporting a fortress 54 as illustrated by Fig. 5 along over a medial line between the cages of the different sides of the room, in which instance it would be preferable to have look-outs 55 and port holes 56, in both side walls 57 and 58 of the fortress, the ventilating means 59 being also provided on both of said side walls to communicate with the banking room interior, it being also understood that ventilation may be had from the exterior, thru conduit means 60.

It is understood that in instances where my invention is embodied in new buildings under construction, the fortress may be constructed integrally with the main building walls as I have shown, while in placing the invention in old structures the fortress is added to the building proper by any means within the realm of carpenters, bricklayers, structural iron workers, or the like.

In the example of the invention shown the fortress and building are constructed mainly of concrete, but it is understood that most any building material may be used, provided an armor plate of steel 35 or 61 or the equiv-

alent is used to face the exposed surfaces of such fortress.

In many bank hold-ups the employees are ordered to go to the basement, under which conditions the steps 20 and stair-way 18 are used to reach the fortress in the same manner as above mentioned.

Under ordinary conditions the fortress interior may be illuminated by any convenient means. During a hold-up, however, it is desirable to have the interior of the fortress dark, by which it would be difficult for bandits to see into the fortress thru the look outs or port holes and ascertain the location of the occupants. To further darken the fortress under such conditions a curtain 62 is suspended from the ceiling 6 over a medial line of the fortress by which arrangement said curtain serves as a screen by which light can scarcely show thru the fortress from one side to the other, and the vision from the outside is greatly hindered as desired.

It is understood that the fortresses such as are herein indicated may be used to protect any business other than banking institutions as desired.

Combined port holes and look-outs 63 with suitable doors are provided for the fortress in the building wall 4, for observations and shooting in the same way as the look-outs in the exterior fortification 17.

If, when entrance to the fortification 13 is made by way of the basement 25, the door 19 should be open, it may be closed on the way thru the basement, by pulling the rope means 62, which engages the door 19 as shown, and which is threaded over the pulley means 63, and allowed to hang down into the basement 25 thru a suitable opening (not shown) in the floor 64. By this arrangement exposure of the parties at the doorway of the door 19 is avoided.

It is understood that both the door 23 and 19 have ordinary self locking door locks 65 (not fully shown) or the equivalent by which said doors automatically lock themselves against attack when closed.

The dot and dash lines 66 indicate an open position of the door 19 and the corresponding position of the rope means 62.

While I have illustrated in a general way, certain structures which may be employed in carrying my invention into effect, it is evident that many modifications may be made in the various details without departing from the scope of the appended claims, it being understood that my invention is not restricted to particular forms, herein described.

I claim as my invention:

1. An interior fortress for business institutions, comprising an over-head enclosure extending across the public room of such institution; a means of reaching said fortress from different floors of such institution, and

different parts of the main floor; observation means at different points of advantage in said fortress; and port hole means for shooting from different points of advantage 5 in said fortress.

2. An interior fortress for business institutions, comprising an over-head enclosure extending across the public room of such institution; a means of reaching said fortress from different floors of such institution, and different parts of the main floor; observation means at different points of advantage in said fortress; port hole means for shooting from different points of advantage 10 in said fortress; and means for closing said port hole means as desired.

3. An interior fortress for business institutions, comprising an over-head enclosure extending across the public room of such institution; a means of reaching said fortress from different floors of such institution, and different parts of the main floor; observation means at different points of advantage 20 in said fortress; port hole means for shooting from different points of advantage in said fortress; means for closing said port hole means as desired; and an exterior fortification directly communicated with said fortress for observing and shooting at bandits, outside of such institution.

4. An interior fortress for business institutions, comprising an over-head enclosure extending across the public room of such institution; a means of reaching said fortress from different floors of such institution, and different parts of the main floor; observation means at different points of advantage 35 in said fortress; port hole means for shooting from different points of advantage in said fortress; an exterior fortification directly communicated with said fortress for observing and shooting at bandits, outside of such institution; and closable observation and port hole means for said fortification.

45 5. An interior fortress for business institutions, comprising an over-head enclosure extending across the public room of such institution; a means of reaching said fortress from different floors of such institution, and different parts of the main floor; observation means at different points of advantage 50 in said fortress; port hole means for shooting from different points of advantage in said fortress; an exterior fortification directly communicated with said fortress for observing and shooting at bandits, outside of such institution; closable observation and port hole means for said fortification; and peep holes in lower regions of said fortification 55 for observing the private departments of said institutions, to detect dishonesty, incompetence or carelessness among the employees within the institution, and for observing and shooting from said fortress to the interior of same; and a means for ventilating said fortress from exterior of such institution.

6. An interior fortress for business institutions, comprising an over-head enclosure extending across the public room of such institution; a means of reaching said fortress from different floors of such institution, and different parts of the main floor; observation means at different points of advantage 70 in said fortress; port hole means for shooting from different points of advantage in said fortress; an exterior fortification directly communicated with said fortress for observing and shooting at bandits, outside of such institution; closable observation and port hole means for said fortification; peep holes in lower regions of said fortification for observing the private departments of 75 said institutions, to detect dishonesty, incompetence or carelessness among the employees within the institution, and for observing and shooting from said fortress to the interior of same; a means for observing and shooting from within said fortress to the exterior of such institution; and a screen means disposed within said fortress to prevent light from showing thru same, 80 for concealing the occupants of such fortress.

7. An interior fortress for business institutions, comprising an over-head enclosure extending across the public room of such institution; a means of reaching said fortress from different floors of such institution, and different parts of the main floor; observation means at different points of advantage 95 in said fortress; port hole means for shooting from different points of advantage in said fortress; an exterior fortification directly communicated with said fortress for observing and shooting at bandits, outside of such institution; a closable observation and port hole means for said fortification; peep holes in lower regions of said fortification for observing the private departments of said institutions, to detect dishonesty, incompetence or carelessness among the employees within the institution, and for observing and shooting from within said fortress to the exterior of such institution; a screen 100 means disposed within said fortress to prevent light from showing thru same, for concealing the occupants of such fortress; and a means for ventilating said fortress from exterior of such institution.

8. An interior fortress for business institutions, comprising an over-head enclosure extending across the public room of such institution; a means of reaching said fortress from different floors of such institution, and different parts of the main floor; observation means at different points of advantage 115 in said fortress; port hole means for shooting from different points of advantage in said fortress; and a means for ventilat- 120

ing said fortress from the exterior of such institution.

9. An interior fortress for business institutions, comprising an over-head enclosure 5 extending across the public room of such institution; a means of reaching said fortress from different floors of such institution, and different parts of the main floor; observation means at different points of advantage 10 in said fortress; port hole means for shooting from different points of advantage in said fortress; a screen means disposed within said fortress to prevent light from showing thru same, for concealing the occupants 15 of such fortress; and a means for ventilating said fortress from the exterior of such institution.

10. An interior fortress for business institutions, comprising an over-head enclosure 20 extending across the public room of such institution; a means of reaching said fortress from different floors of such institution, and different parts of the main floor; observation means at different points of advantage 25 in said fortress; a means for observing and shooting from within said fortress to the exterior of such institution; a screen means disposed within said fortress to prevent light from showing thru same, for concealing 30 the occupants of such fortress; and a means for ventilating said fortress from the exterior of such institution.

11. An interior fortress for business institutions, comprising an over-head enclosure 35 extending across the public room of such institution; a means of reaching said fortress from different floors of such institution; and different parts of the main floor; observation means at different points of advantage 40 in said fortress; port hole means for shooting from different points of advantage in said fortress; peep holes in lower regions of said fortification for observing the private departments of said institutions, 45 to detect dishonesty, incompetence, or carelessness among the employees within the institution, and for observing and shooting from said fortress to the interior of same; a means for observing and shooting from 50 within said fortress to the exterior of such institution; a screen means disposed within said fortress to prevent light from showing thru same, for concealing the occupants of such fortress; and a means for ventilating 55 said fortress from the exterior of such institution.

12. An interior fortress for business institutions, comprising an over-head enclosure extending across the public room of such institution; a means of reaching said fortress from different floors of such institution, and different parts of the main floor; observation means at different points of advantage 60 in said fortress; port hole means for shooting from different points of advantage in said fortress; and a means for observing and shooting from within said fortress to the exterior of such institution.

65 for shooting from different points of advan-

tage in said fortress; an exterior fortification directly communicated with said fortress for observing and shooting at bandits, outside of such institution; closable observation and port hole means for said fortification; peep holes in lower regions of said fortification for observing the private departments of said institutions, to detect dishonesty, incompetence or carelessness among the employees within the institution, and for observing and shooting from said fortress to the interior of same; a means for observing and shooting from within said fortress to the exterior of such institution; a screen means disposed within said fortress to prevent light from showing thru same, for concealing the occupants of such fortress; and a means for ventilating said fortress from the exterior of such institution.

13. An interior fortress for business institutions, comprising an over-head enclosure 85 extending across the public room of such institution; a means of reaching said fortress from different floors of such institution, and different parts of the main 90 floors; observation means at different points of advantage in said fortress; port hole means for shooting from different points of advantage in said fortress; and peep holes in lower regions of said fortification for observing the private departments of said institutions, to detect dishonesty, incompetence or carelessness among the employees within the institution, and for observing and shooting from said fortress to the interior of 95 same.

14. An interior fortress for business institutions, comprising an over-head enclosure 100 extending across the public room of such institution; a means of reaching said fortress from different floors of such institution, and different parts of the main floor; observation means at different points of advantage 105 in said fortress; port hole means for shooting from different points of advantage in said fortress; and an exterior fortification directly communicated with said fortress for observing and shooting at bandits, outside of such institution.

15. An interior fortress for business institutions, comprising an over-head enclosure 110 extending across the public room of such institution; a means of reaching said fortress from different floors of such institution, and different parts of the main floor; observation means at different points of advantage 115 in said fortress; port hole means for shooting from different points of advantage in said fortress; and a means for observing and shooting from within said fortress to the exterior of such institution.

16. An interior fortress for business institutions, comprising an over-head enclosure 120 extending across the public room of such institution; a means of reaching said for- 125

- 5 tress from different floors of such institution, and different parts of the main floor; observation means at different points of advantage in said fortress; port hole means for shooting from different points of advantage in said fortress; and a screen means disposed within said fortress to prevent light from showing thru same, for concealing the occupants of such fortress.
- 10 17. An interior fortress for business institutions, comprising an enclosure over-head runway disposed in the public room of such institution; observation means at different points of advantage in said fortress; port hole means for shooting from different points of advantage in said fortress; and an exterior fortification directly communicated with said fortress for observing and shooting at bandits, outside of such institution.
- 15 18. An interior fortress for business institutions, comprising an over-head enclosure extending across the public room of such institution; door means for reaching said fortress from different floors of such institution, and different parts of the main floor; observation means at different points of ad-

vantage in said fortress; port hole means for shooting from different points of advantage in said fortress; and a means for closing such door means against attack, while on a 30 floor other than that of the door means thus closed.

19. An interior fortress for business institutions, comprising an over-head enclosure extending across the public room of such 35 institution; a means of reaching said fortress from different floors of such institution, and different parts of the main floor; observation means at different points of advantage in said fortress; port hole means for shooting from different points of advantage in said fortress; an exterior fortification directly communicated with said fortress for observing and shooting at bandits, outside of such institution; and a means for 40 closing such door means against attack, while on a floor other than that of the door means thus closed.

In testimony whereof, I have hereunto set my hand on this the 28th day of June, 1926, 50
A. D.

CHARLES H. STROUSE.
